Patented May 27, 1902.

I. YEARNs.

STIRRUP.

(Application filed Aug. 27, 1901.)

(No Model.)

UNITED STATES PATENT OFFICE.

ISAAC YEARNS, OF CRAWFORD, NEBRASKA.

STIRRUP.

SPECIFICATION forming part of Letters Patent No. 700,881, dated May 27, 1902.

Application filed August 27, 1901. Serial No. 73,493. (No model.)

To all whom it may concern:

Be it known that I, ISAAC YEARNS, a citizen of the United States, residing at Crawford, in the county of Dawes and State of Nebraska, have invented a new and useful Stirrup, of which the following is a specification.

The invention relates to improvements in stirrups.

The object of the present invention is to improve the construction of stirrups and to provide a simple, strong, and inexpensive one which will afford a snug fit and a firm support for the foot of a rider and which in event of the rider being thrown from the saddle will automatically release the foot and prevent the rider from being dragged by the animal.

The invention consists in the construction and novel combination and arrangement of parts hereinafter fully described, illustrated in the accompanying drawings, and pointed out in the claims hereto appended.

In the drawings, Figure 1 is a perspective view of a stirrup constructed in accordance with this invention. Fig. 2 is an elevation of the same, partly in section. Fig. 3 is a vertical sectional view.

Like numerals of reference designate corresponding parts in all the figures of the drawings.

1 designates the stirrup frame or body, provided at the top with a cross-bar 2, preferably of tubular form and secured to the sides of the stirrup frame or body by a rod passing through the tubular bar and through the sides of the stirrup frame or body. The sides of the stirrup frame or body are also preferably provided above the rod 4 with slots 5 for the reception of a strap 6; but the slots or openings may be arranged in any other suitable manner, as will be readily understood.

The stirrup is provided with a hinged frame 7, conforming to the general configuration of the stirrup-frame and arranged at the rear side thereof and connected with the stirrup frame or body at the bottom thereof. The bottom of the stirrup frame or body is enlarged to form a rearward extension 8, and it has secured to it a bearing-plate 9, provided at its ends with bearings 10 and having a slot 50 or opening between the same for the reception of coiled springs 11, disposed on the bottom of the hinged frame and connected with

the same and with the stirrup frame or body. The inner ends 12 of the springs are passed through a slot or perforation of the central portion of the bottom of the hinged frame, and the outer ends 13 of the springs are interposed between the bearing-plate 9 and the lower face of the stirrup frame or body. The lower portion of the hinged frame is rounded and is arranged on the exterior of the stirrup frame or body, and the upper portion 14 is flattened and is arranged substantially within the upper portion of the stirrup frame or body, the sides of the hinged frame being bent inward at opposite sides of the stirrup frame or body and engaging the rear edges thereof, as clearly shown in Figs. 1 and 3. The bottom portion of the hinged frame forms a pintle, and the springs operate to hold the hinged frame normally in an upright position against the stirrup frame or body, as clearly shown in Fig. 1. Should a rider be thrown, the frame will swing backward, as indicated in dotted lines in Fig. 3 of the drawings, and will automatically release the foot and carry the same out of the stirrup and prevent the rider from being dragged and injured by the animal. The upper portion of the hinged frame is provided with a transverse top piece 15 or covering 15, preferably constructed of leather and secured by rivets 16 or other suitable fastening devices to the flattened portion of the hinged frame and having a curved lower edge 17, presenting a yielding concave lower face to the instep of the rider to enable the foot to fit snugly within the stirrup. The stirrup is adapted to afford a firm support for the foot, and the top piece 15 forms a shield or guard for preventing the foot from passing too far through the stirrup. The transverse top piece 15 may be ornamented at the front by supplemental pieces 18, stitched at their outer edges and provided at their inner edges with eyelets to enable them to be laced, as shown. The lower concave edge 17 is preferably rolled, as illustrated in Fig. 3, and the bottom of the stirrup is provided with a covering 19, of leather, laced at the bottom and adapted to conceal the bearing-plate and the springs.

It will be seen that the stirrup is exceedingly simple and inexpensive in construction, that it possesses great strength and du-

rability, and that while it affords the necessary snug fit and firm support it is adapted to automatically release the foot of a rider should he be thrown from the saddle.

5 What I claim is—

1. In a stirrup, the combination of a stirrup frame or body, and a hinged upright frame arranged at the back of the stirrup frame or body and conforming to the general configuration of the same and pivotally connected with the said stirrup frame or body at the bottom thereof, whereby it is adapted to swing downward and rearward to release the foot of a rider, substantially as described.
- 15 2. In a stirrup, the combination of a stirrup frame or body, an upright frame arranged at the back of the stirrup frame or body and consisting of an exterior lower portion hinged to the bottom of the stirrup frame or body at the lower face thereof, and an upper portion arranged substantially within the stirrup frame or body, said upright frame crossing the stirrup frame or body and engaging the same, substantially as described.

3. In a stirrup, the combination of a stirrup frame or body, an upright frame arranged at the back thereof and hinged to the bottom of the same, and the transverse top piece extending across the upright frame and having a curved lower edge, substantially as described.

4. In a stirrup, the combination of a stirrup frame or body, an upright frame hinged to the bottom of the stirrup frame or body and provided with a flattened upper portion, the transverse top piece secured to the flattened portion of the upright frame, and a spring for holding the upright frame normally in such position, substantially as described.

In testimony that I claim the foregoing as my own I have hereto affixed my signature in the presence of two witnesses.

ISAAC YEARN.
